LINUS A. BRAUN, OF MINNEAPOLIS, MINNESOTA

WOOD-PULP PRODUCTION AND REFINING

Application filed February 5, 1929. Serial No. 337,684.

This invention relates to improvements in means and methods for producing and refining fibrous pulp for paper making.

The primary object of this invention is the provision of an improved pulp making machine by means of which wood and other appropriate material may be readily reduced to pulp and properly refined and treated, to provide properly strengthened fiber pulp which may be economically used for the manufacture of paper, building board, and insulating or other materials.

A further object of this invention is the provision of an improved means for reducing raw materials, such as wood, to pulp, in an economical manner, by grinding the raw material upon a suitable perforated or roughened surface in such a manner as to break down and separate the fibers of the raw material and reduce them to a pulp form. The improved means may also be used for the refining of paper pulp to further strengthen the fibers thereof.

A further object of this invention is the provision of an improved machine for reducing fibrous pulp, by grinding the pulp, or in fact the raw material, if desired, between relatively moving bodies, one of which, at least, has an abrasive surface, preferably perforated and provided with cutting projections, such as found in expanded metal, in order to reduce the coarse fibers and strengthen the fibrous pulp to a suitable condition by ruffing and combing the fibrous pulp through bearing and tearing actions, so as to increase the "freeness" and "pop" test of the same.

A further object of this invention is the provision of improved means for reducing and refining wood fiber, in connection with the manufacture of paper, which consists in the provision of a screen wherein the fibrous stock is received and retained until it is sufficiently reduced that it will pass through the perforations of the screen; the said screen being free of openings through which unreduced and unrefined stock may pass; means being provided in the screen to accelerate and insure reduction and refining of fibers to the

point that they may pass through the screen perforations.

Other objects and advantages of this invention will be apparent during the course of the following detailed description. 55

In the accompanying drawings, forming a part of this specification, and wherein similar reference characters designate corresponding parts throughout the several views,

Figure 1 is a longitudinal sectional view 60 taken through the improved machine for producing refining and strengthening fibrous materials.

Figure 2 is an end view of the machine, at the receiving end thereof. 65

Figures 3, 4, 5 and 6 are sectional views taken substantially on their respective lines in Figure 1 of the drawings.

In the drawings, wherein for the purpose of illustration is shown only a preferred embodiment of this invention, the letter A may generally designate the improved machine, which may comprise a section B wherein the pulp or raw material is initially treated by grinding, cutting, and tearing the same to a fibrous condition, after which the pulp is treated in a section C of the machine A for beating, refining, and centrifugally straining the pulp. 70

The sections B and C of the machine A are 80 provided with a common shaft D, which extends axially through the housings E and F of the machine parts B and C respectively.

In the section B, the housing E receives means K, in the nature of an abrasive or 85 perforated body, preferably heavy expanded metal, case hardened, which cooperates with the crushing and hammering means L for tearing, cutting, and stripping the fibers from raw material or from pulp to further refine 90 the same.

The pulp is delivered from the section B of the machine A into a chamber of screen means P of the section C, and therein beater means M operates thereon for centrifugally 95 throwing and distributing the pulp against screen means P, thru which the desirable fibers, in pulp condition, are passed into the housing F.

The housing E is preferably of cylindrical 100

formation, disposed upon a horizontal axis. It may be cast, or otherwise formed, and is hollow, providing a passageway therethrough forming the chamber wherein the pulp or raw material is reduced. At one end thereof is disposed the entrance end or section R of the machine A, which preferably comprises a frusto-conical body 10 formed of upper and lower sections 11 and 12, shown in Figure 2 of the drawings, horizontally divided along the axis thereof, and outwardly flanged and bolted together as at 16. At its smaller end it provides a wall 17 forming a bearing for one end of the shaft D; said wall 17 having anti-friction bearings 19 therein for receiving the end of the shaft. The frusto-conical body 10 is hollow, providing a frusto-conical shaped chamber 20, and at the larger end, the frusto-conical body 10 is flanged at 21 and bolted at 22 to the end flange 23 of the hollow cylindrical shaped housing E. The housing E and the body of the entrance end structure R, are provided with supporting legs or brackets 25 and 26 respectively, which support the machine sections on a platform or floor surface. The upper part 11 of the entrance end body 10 is provided with an inlet conduit or connection 30, thru which the pulp or raw material is fed into the chamber 20 and thence flows or is forced into the chamber of the housing B, for reduction upon the cutting surface K by the rotary means L. The body 10 may be provided with suitable inlet connections 33, to which conduits may be connected for delivering streams of water or other fluid into the mass of raw material or pulp which is entering the machine, to force the latter along the housing E.

40 The housing E is preferably of uniform diameter and disposed with the horizontal shaft D axially therethrough. This housing is divided along its length, and at its end remote from the inlet end of the machine it is provided with a flange 34 adapted to be bolted as at 35, shown in Figure 3, to a similar flange 36 provided on the inlet end of the housing F. If found suitable the housing may be made of one piece, or of any approved construction.

45 Within the housing E is disposed the means K, preferably in the nature of a screen in abutment with the interior peripheral surfaces of the said housing, provided with means thereon to cut, tear, and comb the fibers of the wood, or other raw material to a reduced separated condition. This means K is preferably a sheet of expanded metal, relatively heavy and case hardened; the raised portions of which are preferably arranged diagonal to the axis of the housing, so as to permit the rotary hammer means L to strip the fibers of the material entering the machine by means of a cutting and tearing action between the screen and the rotary means.

The primary essential is that the interior surface shall be provided with a roughened, abrasive, or cutting surface, and which is found to be most economically provided by disposing expanded metal within the housing. 70

The shaft D extends axially through the housing E and is supported at the entrance end of the machine A on the bearing 19, and at its opposite end it is supported in a suitable bearing 40 to be subsequently described. 75

The rotary means L which acts to move the mass of material in the machine with a shearing action across the abrasive expanded metal surfaces, preferably comprises a plurality of spaced discs 41 keyed or shrunk or otherwise connected as at 42 upon the shaft. These discs are centrally disposed upon the shaft and in preferably uniform spaced relation. In the spaces between the discs 41, near the marginal portions of said discs, are disposed pivoted macerating elements or hammers 44, which are preferably of heavy metal, and may be rectangular in formation. The hammers 44 are connected in longitudinal series in the spaces between the discs 41; preferably four of such series being provided, 90° apart about the discs 41, as shown in Figure 3 of the drawings. Each series of said hammers 44 is held in position, preferably, by a common pivot pin or pintle 46, which is threaded thru suitable openings in the discs 41, and at the ends said pins 46 are detachably held upon the discs by cotter pins 48 or the like. The hammers 44, as before mentioned, are elongated, and preferably rectangular in form, and each is pivoted closer to one end thereof than the other end, so that by centrifugal action, during the rotation of the rotary means L; the heavier 100 ends of the hammers 44 will be swung towards the perforated screening or expanded metal K to act on the mass of material or pulp and hit it with considerable force in a shearing relation against the cutting portions of the screen K, so as to strip or reduce the fibers, which are of course washed from the perforations of the screen by the liquid entering the machine, to cause the pulp mass to travel into the forward end of 105 the machine where the pulp mass is beaten and pressed through a screen. 110

The housing F is horizontally aligned and connected with the housing E, and comprises a divided cylindrical body portion 50 which may be of the same size as the cylindrical housing E. The shaft D extends axially through the housing F, and at the delivery end of the machine is supported in the bearing 40 above mentioned, and to be subsequently described. 120

The cylindrical shaped screen P is concentrically supported in the housing F in spaced relation with the inner peripheral surfaces of the latter, by means of substan- 125 130

tially Z-shaped brackets or rails 54, best shown in Figure 5, which are detachably bolted to the housing F and the screen P. The pulp fibers are adapted to enter the screen P from the housing E, and be pressed through the perforations of the screen into the annular compartment 55 between the screen P and the housing F, from whence they may pass by gravity flow, or otherwise if found necessary, into the delivery end of the machine. The entrance end of the cylindrical screen P is open, and the housing F is provided with a sloping guide flange 55^a, which flares from the connecting location of the housings E and F, in a convergent relation to the facing edge or end of the screen, where it slidably abuts said end of the screen, for the purpose of guiding the pulp from the housing E into the screen P without direct admission to the compartment 55.

The screen P at the delivery end of the machine is provided with an end wall 57, in the form of a disc, resting on the shaft D, and held in place by collar 58 keyed to the shaft. This wall 57 may or may not be perforated.

Within the cylindrical shaped screen P, there is disposed a paddle-like beater M, comprising a plurality of longitudinally extending paddle blades 58, which are connected with the shaft D by means of preferably radial arms 59. Three sets of the arms 59 are provided, as shown in Figure 1, and each of the blades 58 is disposed for substantially the length of the compartment within the screen P. The arms 59 are provided with slots 60 at the outer ends thereof, shown in Figure 1, which receive connecting bolts 61 by means of which the blades 58 may be adjustably connected to their respective supporting arms 59, for adjustment at various distances with respect to the inner periphery of the perforated screen P. It is quite obvious that this adjustment is important, since the beater should conform to the characteristic of the particular pulp being treated.

Within the area of the flared entrance of the housing F, there is disposed an imperforate disc-like baffle 65, which is keyed to the shaft D for rotation therewith. This baffle 65 is spaced at its peripheral edges with respect to the flared surfaces of the flange 55^a, so that the pulp flow is directed from the housing E into the screen P in an annular path at a location where it can be effectively operated upon by the blades of the paddle-like beater M, and centrifugally treated in an efficient manner, without liability of too much pulp entering the screen P for treatment along the axis of the shaft.

The delivery end of the machine preferably comprises a divided frusto-conical shell 80, having an annular flange connection at 81 with the delivery end of the housing F. The

shell 80 provides a tapered compartment 82, within which the pulp flows as it is strained or forced through the perforated cylinder screen P, and therefrom exits through a bottom outlet conduit 84 of any approved nature. The shell 80 is supported by a standard 85, and an end wall 86 of the shell supports the bearing 40 therein, wherein the shaft D rotates.

The operation of the invention will be apparent from the foregoing. The wood chips or other material, or even pre-treated pulp may be fed into the entrance end of the machine for treatment. It is first broken up by means of the rapidly revolving hammers centrifugally forcing and shearing the pulp or raw material against the projecting cutting portions of the expanded metal, if the latter is used, tearing, combing, and reducing the material to a fibrous pulp. The stock is then carried into the cylindrical screen, by the force of the liquids introduced with the stock, and retained in this screen until beaten and operated upon by centrifugal force to further reduce the same to a characteristically fine condition, in order to permit it to pass through the perforations. This operation greatly strengthens the fibers as to "freeness" and "pop" tests.

Various changes in the steps of the method, and in the shape, size, and arrangement of parts may be made to the form of invention herein shown and described, without departing from the spirit of the invention or the scope of the claims.

I claim:

1. In a pulp reducing machine the combination of a container of substantially cylindrical formation having an inner pulp shearing and cutting surface, hammer means operating in spaced relation with said cutting surface for urging pulp and fibrous material in a shearing relation against the cutting surface, means to feed raw material or pulp into said container, means to supply a liquid in a longitudinally flowing relation to said container for carrying the pulp therewith, a screening container into which the pulp flows from the first mentioned container, and means operating in the screen container for centrifugally urging the pulp through the perforations of the screen container.

2. In a fiber producing or refining machine in which the fibers are directly acted upon, the combination of means for reducing fibrous material including a rotary substantially cylindrical shaped container of expanded metal provided with an inner peripheral shearing face against which the fibrous material is roughened, combed, and torn to a reduced condition, said container being horizontally disposed, means for feeding the fibrous material into one end of the container, and baffle means at the other end of the container to retard the flow of stock therefrom.

3. In a fiber producing or refining machine in which the fibers are directly acted upon, the combination of means for reducing fibrous material including a rotary substantially cylindrical shaped container of expanded metal provided with an inner peripheral shearing face against which the fibrous material is roughened, combed, and torn to a reduced condition, said container being horizontally disposed, means for feeding the fibrous material into one end of the container, and baffle means at the other end of the container to retard the flow of stock therefrom, said baffle means comprising a disc disposed in the container to provide an annular escape opening thereabout from the container.
4. In a fiber producing and refining machine in which the fibers are directly acted upon, the combination of a cylindrical shaped container having an internal cutting face whereon fibrous material may be rotated en masse for reducing the same, a screening container, baffle means between said containers for retarding the flow of stock from the first to the latter, and means acting in the last mentioned container for reducing fibrous pulp to a strengthened condition by ruffing, combing and tearing the fibrous material against the screen until the reduced fibrous material is passed through the perforations of the screen.
5. In a pulp reducing machine the combination of an elongated housing having an entrance at one end and a delivery at the other end, means in the housing adjacent the entrance for reducing fibrous material to a fibrous pulp, and means to receive the fibrous pulp from the last mentioned means and preserve screen the same.
6. In a pulp reducing machine the combination of a horizontally elongated housing, rotary pulp reducing means at one end of the housing, means to deliver fibrous material to said rotary reducing means for reducing fibrous material to a pulpy condition, and means in the housing cooperating with the last mentioned means for screening the pulp prior to discharge from the housing.
7. In a pulp reducing machine the combination of a horizontally elongated housing, rotary pulp reducing means at one end of the housing, means to deliver fibrous material to said rotary reducing means for reducing fibrous material to a pulpy condition, means in the housing cooperating with the last mentioned means for screening the pulp prior to discharge from the housing, and means between the first and second above mentioned means to retard the flow of pulp into the last mentioned means.

LINUS A. BRAUN.
